DUMPING WHEELBARROW

Albert R. Hines, Columbus, Ga.

Application December 10, 1947, Serial No. 790,899

1 Claim. (Cl. 298—24)

1 This invention relates to a combined reel and barrow.

An object of this invention is to provide a wheeled barrow or container which includes an upwardly opening body having a latched closure in the front portion thereof so that the contents of the container may be selectively discharged, the container having a rearwardly extending handle between which is rotatably mounted a hose reel, and the handles also having laterally projecting brackets for holding the handles of tools which are disposed in the barrow or container.

Another object of this invention is to provide a multi-purpose article including a wheeled body having a rearwardly projecting handle on which is adapted to be detachably mounted a hose reel, and the handle having fixed thereto a pair of tool handle supporting brackets. The body is formed with a closure which is spring-pressed to closed position, being hinged at the upper edge thereof so that upon release of the latch means the weight of the material in the body will swing the door to open or discharging position.

To the foregoing objects, and others which may hereinafter more fully appear, the invention consists of the novel construction, combination and arrangement of parts, as will be more specifically referred to and illustrated in the accompanying drawings, but it is to be understood that changes, variations, and modifications may be resorted to which fall within the scope of the invention as claimed.

In the drawings:

Figure 1 is a detailed side elevation, partly broken away and in section, of a combined reel and wheel barrow.

Figure 2 is a fragmentary top plan of the rear portion of the device.

Figure 3 is a front elevation, partly broken away and in section, of the device.

Figure 4 is a fragmentary sectional view taken on the line 4—4 of Figure 1.

Figure 5 is a fragmentary sectional view taken on the line 5—5 of Figure 3.

Figure 6 is a fragmentary sectional view taken on the line 6—6 of Figure 3.

Figure 7 is a fragmentary sectional view taken on the line 7—7 of Figure 4.

Referring to the drawings, the numeral 10 designates generally a body or receiver which is formed of opposite side walls 11, a rear wall 12, a bottom wall 13 and a front wall 14. The front wall 14 is formed with an opening at a point downwardly from the upper edge thereof which

is adapted to be normally closed by means of a spring-pressed closure 15 hingedly mounted as at 16 on the lower edge of the front wall 14. A plurality of bowed springs 17 secured to the forward side of the front wall 14 engage the closure 15 for normally urging the latter to closed position. The closure 15 has secured to the lower edge thereof a plurality of keepers 18 which are engaged by spring-pressed latch members or bolts 19. The latch members or bolts 19 are each pivotally mounted between a pair of ears 20 which are fixed to the bottom wall 13 at the forward portion of the latter and each latch member or bolt 19 includes a downwardly extending ear 21.

An elongated rod 22 is extended through the several ears 21 and is formed with an upwardly and rearwardly extending rod member 23 which is slidable through a pair of angle guide members 24 fixed to one side of the receiver 10. The upper end of the rod 23 has secured thereto a rock lever or latch operator 25 which is pivotally secured as at 26 to the container or receiver 10. The container or receiver 10 is movably mounted through the medium of a U-shaped axle 27 having the bight 28 thereof secured by means of clamping plates 29 to a plurality of longitudinally extending and spaced apart bottom reinforcing bars 30 which are secured by fastening means 31 to the lower side of the bottom 13.

The axle 27 includes upwardly extending arms 32 extending upwardly on the outer sides of the side walls 11 and the arms 32 terminate in outwardly extending spindles or trunnions 33 on which wheels 34 are rotatably mounted. The container or receiver 10 has secured thereto a U-shaped upwardly and rearwardly extending handle 35 which has formed integral with the parallel sides 36 thereof downwardly extending extensions 37 which are fixed by fastening means 38 to the rear wall 12. The extensions 37 terminate at their lower ends in downwardly and rearwardly inclined legs 39 and the latter terminate in horizontally disposed feet 40 adapted to engage the ground for holding the container or receiver 10 in substantially upright position.

The parallel sides 36 of the handle 35 have disposed therebetween a hose reel 41. The hose reel 41 includes a shaft 42 which is rotatably and removably mounted in L-shaped bearing members 43 which are formed with upper base members 44 secured by fastening means 45 to the lower sides of the parallel arms 36. The lower side or arm 46 of each L-shaped member 43 is spaced downwardly from the base 44 so that the reel shaft 42 may be disengaged from the bearing

or support 43 by upward and rearward movement of the shaft 42. The vertical side 41 of the L-shaped member 43 is disposed forwardly and as the arms 36 normally incline downwardly and forwardly the shaft 42 will be retained in the open bearing formed of the L-shaped member 43. A pair of U-shaped bracket members 48 are secured to the upper sides of the parallel members 36 and are adapted to be engaged by the handles of garden tools which are extended forwardly and downwardly into the container or receiver 10. The U-shaped members 48 include a vertical inner bar 49 which is secured by fastening means 50 to an attaching plate 51. The attaching plate 51 is secured by means of the fastening members 45 to the side members 36. The latch members 19 are adapted to be constantly urged to latching position by means of springs 52 which are secured to the reinforcing bars 30 and engage the ears 21.

In the use and operation of this device the receiver or container 10 comprising the wheel barrow may have any desired material disposed therein such as leaves, dirt or the like and when it is desired to discharge the material from the receiver 10, latch operating lever 25 is rocked downwardly and forwardly thereby swinging the latch members 19 to released position. The pressure of the material in the receiver or container 10 will swing closure 15 to an open position. If desired, the hose reel 41 may be retained on the handle 35 during the use of the container or receiver 10 but if the hose is not to be used the reel 41 may be easily and quickly removed by moving the reel upwardly and rearwardly to disengage the shaft 42 from the supporting members 43.

I claim:

A wheelbarrow comprising a container, wheels rotatably mounted beneath said container, said container being formed of upwardly divergent arcuate front and rear walls, parallel side walls, and a flat bottom wall, a downwardly opening closure hingedly carried by said front wall, bowed leaf spring means secured to said container adjacent the hinge portion of said closure

yieldably urging said closure to closed position, a plurality of keepers fixed to the bottom of said closure, a plurality of spring pressed latch members adapted to engage said keepers, a transverse shaft rockably carrying said latch members secured to said container, a rod extending from said shaft along one of said side walls, an operating lever rockably carried by one side wall and connected to said rod, a handle for said container, said handle comprising a single unitary tubular member formed of a transverse central portion from each end of which portions extend forwardly and downwardly toward said wheelbarrow, arcuate portions conforming in configuration to said rear wall depending from said last mentioned portions along opposite sides of said arcuate rear wall, each of said arcuate portions terminating in a rearwardly extending downwardly inclined leg portion, which last mentioned portions in turn terminate in substantially horizontal extremities to form a support for said barrow, and means securing said arcuate portions to said rear wall.

ALBERT R. HINES.
